(57) **ABSTRACT**

Interference between an intake manifold and a fuel pipe during a vehicle front collision is prevented in an engine which is longitudinally mounted in an engine room. A vehicle component is arranged on the front side of the intake manifold, and the fuel pipe is arranged on the rear side of the intake manifold. The intake manifold includes a plurality of independent intake pipe portions arranged side by side in the vehicle front-rear direction which branch for each of the cylinders of the engine; and a plurality of coupling portions that each couple adjacent independent intake pipe portions to each other in an integral manner. A first coupling portion of the plurality of coupling portions positioned on the frontmost side has a lower rigidity than a third coupling portion of the plurality of coupling portions positioned the rearmost side.

INTAKE MANIFOLD STRUCTURE

TECHNICAL FIELD

The technology disclosed herein belongs to a technical field relating to an intake manifold structure.

BACKGROUND

Hitherto, consideration has been given to dealing with a vehicle collision using the structure of an intake manifold connected to an engine.

For example, Japanese Patent Laid-Open No. 2012-158994 discloses a front structure of an engine laterally placed in an engine room such that the cylinder array direction is in the vehicle width direction. In the front structure, an intake manifold made of resin is fastened on the vehicle front side of the engine at an upper portion and a lower portion thereof, a fuel distribution pipe that extends in the crank shaft line direction is arranged below an upper mounting portion of the intake manifold, the intake manifold is formed in a manner of being split to the side close to the engine and the side far from the engine and is composed of a plurality of joined split bodies, the strength of a base split body on the side close to the engine is set to be higher than that of another split body on the side far from the engine, an oil separator cover made of resin is provided on the vehicle front face side of the engine, and retreat restriction portions that abut against each other in the process of displacement of the base split body at the time of a collision are provided on the base split body and the oil separator cover.

SUMMARY

When the engine is arranged such that the cylinder array direction is in the vehicle front-rear direction, the intake manifold is arranged on one side of the engine in the vehicle width direction. At this time, a fuel pump and a fuel pipe connected to the fuel pipe may be arranged on a portion of the engine on the rear side thereof, and vehicle components such as an alternator may be arranged on a portion of the engine on the front-side thereof. In the configuration as above, at the time of a vehicle front collision, the vehicle components retreat and abut against the intake manifold. As a result, when the intake manifold retreats in a pileup manner, the intake manifold might interfere with the fuel pipe.

The engine structure described in Japanese Patent Laid-Open No. 2012-158994 is a configuration that prevents interference between the intake manifold and the fuel pipe on the premise that the engine is laterally placed in the engine room. Therefore, the engine structure does not prevent the interference between the intake manifold and the fuel pipe also for the case where the engine is longitudinally placed in the engine room. Therefore, there is room for improvement from the viewpoint of preventing the interference between the intake manifold and the fuel pipe when the engine is longitudinally placed in the engine room.

The technology disclosed herein has been made in view of this point, to prevent interference between an intake manifold and a fuel pipe at the time of a vehicle front collision when an engine is longitudinally mounted in an engine room.

In order to solve the abovementioned problem, in the technology disclosed herein, an intake manifold structure including an intake manifold connected to a portion of an engine on one side of the engine in a vehicle width direction has the following configuration, the engine being longitudi-

nally placed in an engine room such that a cylinder array direction is in a vehicle front-rear direction, the engine having three or more cylinders. A vehicle component is arranged on a vehicle front side of the intake manifold, and a fuel pipe through which fuel flows is arranged on a vehicle rear side of the intake manifold so as to extend in an up-down direction. The intake manifold includes a plurality of independent intake pipe portions formed so as to branch and arranged side by side in the vehicle front-rear direction to provide one of the intake pipe portions for each of the cylinders; and a plurality of coupling portions that each couple adjacent independent intake pipe portions out of the plurality of independent intake pipe portions to each other in an integral manner. A front-side coupling portion of the plurality of coupling portions that is the coupling portion positioned on a frontmost side is configured to have a lower rigidity than a rear-side coupling portion of the plurality of coupling portions that is the coupling portion positioned on a rearmost side.

With this configuration, the rigidity of the portion on the vehicle front side is low in the independent intake pipe portions. Therefore, at the time of a vehicle front collision, the independent intake pipe portions on the vehicle front side deform by the collision load. As a result, the collision load can be absorbed as much as possible. The independent intake pipe portions on the vehicle rear side can be prevented from deforming as much as possible by causing the rigidity thereof to be relatively high. In particular, the independent intake pipe portions on the vehicle front side deform and absorb the collision load. As a result, the load received by the independent intake pipe portions on the vehicle rear side can be reduced. Therefore, the deformation of the independent intake pipe portions on the vehicle rear side can be prevented as much as possible. As a result, a case where the intake manifold and the fuel pipe interfere with each other at the time of a vehicle front collision can be prevented.

The intake manifold structure may have a configuration in which the front-side coupling portion has a through hole that passes through the front-side coupling portion in the vehicle width direction.

With this configuration, the rigidity of the front-side coupling portion can be reduced, and the independent intake pipe portions on the vehicle front side can be caused to easily deform. As a result, the deformation of the independent intake pipe portions on the vehicle rear side can be prevented as much as possible, and hence a case where the intake manifold and the fuel pipe interfere with each other at the time of a vehicle front collision can be prevented.

The intake manifold structure may have a configuration in which the engine is a four-cylinder engine, and an intermediate coupling portion positioned between the front-side coupling portion and the rear-side coupling portion out of the plurality of coupling portions has an upper end portion at a position of which is lower than upper end portions of the front-side and rear-side coupling portions.

With this configuration, the connection rigidity of the independent intake pipe portions on the vehicle front side and the independent intake pipe portions on the vehicle rear side can be caused to be low. Therefore, a case where the collision load input to the independent intake pipe portions on the vehicle front side is transmitted to the independent intake pipe portions on the vehicle rear side can be prevented. As a result, at the time of a vehicle front collision, the deformation of the independent intake pipe portions on the vehicle rear side can be prevented while deforming the independent intake pipe portions on the vehicle front side.

As a result, a case where the intake manifold and the fuel pipe interfere with each other at the time of a vehicle front collision can be prevented.

The intake manifold structure in which the intermediate coupling portion is formed may have a configuration in which the intake manifold further includes: a surge tank portion that is connected to one end portion of each of the plurality of independent intake pipe portions and is for distributing intake air to each of the independent intake pipe portions; a mounting portion for integrating other end portions of the plurality of independent intake pipe portions with each other and mounting the intake manifold to the engine; a front-side cross-linking portion that is provided in a position in which the front-side coupling portion is formed in the vehicle front-rear direction and couples the mounting portion and the surge tank portion to each other; and a rear-side cross-linking portion that is provided in a position in which the rear-side coupling portion is formed in the vehicle front-rear direction and couples the mounting portion and the surge tank portion to each other.

With this configuration, the collision load can be easily transmitted between the independent intake pipe portions for two cylinders on the front side, and the deformation of the independent intake pipe portions on the vehicle front side can be prompted. Meanwhile, in the independent intake pipe portions for two cylinders on the rear side, the load after the absorption by the independent intake pipe portions on the front side can be appropriately received by causing the load to be easily transmitted between the independent intake pipe portions. As a result, a case where the intake manifold and the fuel pipe interfere with each other at the time of a vehicle front collision can be prevented.

The intake manifold structure may have a configuration in which the intake manifold is made of resin.

With this configuration, as compared to when the intake manifold is made of metal, the structure in which a difference in rigidity occurs between the front-side coupling portion and the rear-side coupling portion is easily obtained. As a result, the structure that prevents the interference between the intake manifold and the fuel pipe interfere at the time of a vehicle front collision can be easily realized.

In another aspect of the technology disclosed herein, an intake manifold structure including an intake manifold connected to a portion of an engine on one side of the engine in a vehicle width direction has the following configuration, the engine being longitudinally placed in an engine room such that a cylinder array direction is in a vehicle front-rear direction, the engine having three or more cylinders. A vehicle component is arranged on a vehicle front side of the intake manifold, and a fuel pipe through which fuel flows is arranged on a vehicle rear side of the intake manifold so as to extend in an up-down direction. The intake manifold includes a plurality of independent intake pipe portions formed so as to branch and arranged side by side in the vehicle front-rear direction to provide one of the intake pipe portions for each of the cylinders. A rear-side intake pipe group, of a plurality of intake pipe groups each composed of adjacent independent intake pipe portions out of the plurality of independent intake pipe portions, is positioned closest to the vehicle rear side and has a coupling portion that integrally couples the adjacent independent intake pipe portions to each other, and a front-side intake pipe group of the plurality of intake pipe groups is positioned closest to the vehicle front side and does not have the coupling portion.

With this configuration, the rigidity of the portion of the front-side intake pipe group is reduced. Therefore, the front-side intake pipe group deforms by the collision load at

the time of a vehicle front collision. As a result, the collision load can be absorbed as much as possible. The front-side intake pipe group deforms and absorbs the collision load. As a result, the load received by the rear-side intake pipe group can be reduced. Therefore, the deformation of the rear-side intake pipe group can be prevented as much as possible. As a result, a case where the intake manifold and the fuel pipe interfere with each other at the time of a vehicle front collision can be prevented.

As described above, according to the technology disclosed herein, a case where the intake manifold and the fuel pipe interfere with each other at the time of a vehicle front collision can be prevented.

15 BRIEF DESCRIPTION OF THE DRAWINGS

FIG. 1 is a side view of an engine having an intake manifold structure according to an exemplary embodiment.

FIG. 2 is a front view illustrating the intake manifold of the engine in an enlarged manner.

FIG. 3 is a rear view illustrating the intake manifold of the engine in an enlarged manner.

FIG. 4 is a perspective view of the intake manifold seen from the upper left side and the rear side.

FIG. 5 is a side view of a first split piece of the intake manifold seen from the right side.

FIG. 6 is a plan view of the intake manifold.

FIG. 7 is a cross-sectional view taken along a plane equivalent to line VII-VII in FIG. 6.

FIG. 8 is cross-sectional view taken along a plane equivalent to line VIII-VIII in FIG. 6.

FIG. 9 is a cross-sectional view taken along a plane equivalent to line IX-IX in FIG. 6.

FIG. 10 is an enlarged perspective view illustrating a fifth fastening portion in an enlarged manner.

FIG. 11 is a perspective view of the intake manifold seen from the lower left side and the rear side.

FIG. 12 is a perspective view of a second split piece of the intake manifold.

40 DETAILED DESCRIPTION

An exemplary embodiment is described in detail below with reference to the drawings. In the description below, 45 front, rear, left, right, up, and down with respect to the vehicle are simply referred to as front, rear, left, right, up, and down. In the left-right direction, the left side when the front side is seen from the rear side is referred to as the left, and the right side thereof is referred to as the right.

FIG. 1 is a side view of an engine 1 seen from the left side. The engine 1 is a multiple cylinder engine and specifically has four cylinders. The engine 1 is longitudinally placed in an engine room of a vehicle such that the cylinder array direction is in the front-rear direction. The engine 1 is disposed such that the left side is the intake side and the right side is the exhaust side.

An intake manifold 10 for introducing intake air into the cylinders is connected to the left side face of a cylinder head of the engine 1. The intake manifold 10 is made of synthetic resin. As illustrated in FIG. 2 and FIG. 3, the intake manifold 10 has a plurality of (four herein) independent intake pipe portions 11 formed so as to branch for each cylinder and arranged side by side in the front-rear direction, a surge tank portion 13 that is connected to a lower end portion of each independent intake pipe portion 11 and distributes the intake air to each independent intake pipe portion 11, and an intake air introduction pipe 14 that extends to the front side from

a portion of the surge tank portion 13 on the front side and the upper side thereof and is for introducing intake air from an intake pipe (not shown). Detailed configuration of the intake manifold 10 is described below.

As illustrated in FIG. 1, on the front side of the intake manifold 10, a vehicle component, in particular, an alternator 2 serving as an engine accessory is arranged. The alternator 2 generates electric power by the rotation of the engine and functions as a starter at the time of the starting of the engine. As illustrated in FIG. 1 and FIG. 2, the alternator 2 is arranged in the same position as the surge tank portion 13 and is arranged in a position that overlaps with the surge tank portion 13 when seen from the front side.

As illustrated in FIG. 1 and FIG. 3, a fuel pipe 3 through which fuel flows is arranged on the rear side of the intake manifold 10. As illustrated in FIG. 3, the fuel pipe 3 includes a low-pressure pipe 3a that supplies fuel to a fuel pump 4 from a fuel tank (not shown), and a high-pressure pipe 3b through which fuel of which pressure has been raised by the fuel pump 4. The low-pressure pipe 3a is made of a flexible resin tube. The high-pressure pipe 3b is made of a metal pipe. Both of the low-pressure pipe 3a and the high-pressure pipe 3b are arranged so as to extend in the up-down direction. An end portion of the high-pressure pipe 3b on the downstream side thereof is connected to a rear-side end portion of a fuel distribution pipe 5. The fuel distribution pipe 5 is a distribution pipe for supplying fuel to each cylinder and extends in the front-rear direction along the left side face of the engine 1. As illustrated in FIG. 3, the fuel distribution pipe 5 is arranged in a position between a mounting portion 33 described below and the surge tank portion 13.

The intake manifold 10 according to the present embodiment is described in detail below with reference to FIG. 4 to FIG. 12.

As illustrated in FIG. 4, each independent intake pipe portion 11 of the intake manifold 10 is integrally connected to a portion of the surge tank portion 13 on the lower left side thereof. Each independent intake pipe portion 11 extends so as to be curved to the upper side and the right side from a portion connected to the surge tank portion 13 and is disposed so as to cover the upper side of the surge tank portion 13. At least some (in particular, the independent intake pipe portions 11 positioned on the front side) of the plurality of independent intake pipe portions 11 cover the upper side of the intake air introduction pipe 14. Each independent intake pipe portion 11 is in communication with the inside of the surge tank portion 13 at a lower end portion. The intake air passes through the intake air introduction pipe 14 and is accumulated in the surge tank portion 13. Then, the intake air passes through each independent intake pipe portion 11 and is introduced into the cylinder. In the description below, an independent intake pipe group composed of two independent intake pipe portions 11 on the front side may be referred to as a first intake pipe group 11a (see FIG. 1) and an independent intake pipe group composed of two independent intake pipe portions 11 on the rear side may be referred to as a second intake pipe group 11b (see FIG. 1).

As illustrated in FIG. 6, each independent intake pipe portion 11 has, in the order from the intake air upstream side, a main passage portion 12, an intermediate portion 44 (a portion of a second split piece 40 described below), and a downstream-side end portion 34 (a portion of a first split piece 30 described below). Each independent intake pipe portion 11 is formed by coupling the main passage portion 12, the intermediate portion 44, and the downstream-side end portion 34 to each other. The main passage portions 12

of the independent intake pipe portions 11 are hereinafter referred to as a first main passage portion 12a, a second main passage portion 12b, a third main passage portion 12c, and a fourth main passage portion 12d from the order from the front side. When the main passage portions are not distinguished from each other, the main passage portion is simply referred to as the main passage portion 12.

The main passage portions 12 of the independent intake pipe portions 11 are integrated with each other across the entirety in the longitudinal direction thereof. In other words, the main passage portions of the independent intake pipe portion 11 adjacent to each other are coupled to each other via each of coupling portions positioned between both of the independent intake pipe portions 11. The coupling portions include a first coupling portion 81 that couples the first main passage portion 12a and the second main passage portion 12b to each other, a second coupling portion 82 that couples the second main passage portion 12b and the third main passage portion 12c to each other, and a third coupling portion 83 that couples the second main passage portion 12b and the third main passage portion 12c to each other. The first coupling portion 81 is equivalent to a front-side coupling portion, the second coupling portion 82 is equivalent to an intermediate coupling portion, and the third coupling portion 83 is equivalent to a rear-side coupling portion.

As illustrated FIG. 1 and FIG. 7, the first coupling portion 81 has an upper end portion that extends to a place in the vicinity of upper ends of the independent intake pipe portions 11. The first coupling portion 81 has a plurality of lateral ribs 81a that extend in the front-rear direction. As illustrated in FIG. 1, the number of the lateral ribs 81a of the first coupling portion 81 is smaller than the number of lateral ribs 82a of the second coupling portion 82 and the number of lateral ribs 83a of the third coupling portion 83. More specifically, the lateral ribs 81a are not formed in a portion of the first coupling portion 81 on the lower side thereof. The first coupling portion 81 has a through hole 81b in a portion between the lateral rib 81a positioned on the uppermost side out of the plurality of lateral ribs 81a and the upper end portion so as to pass therethrough in the vehicle width direction.

As illustrated in FIG. 1 and FIG. 8, the position of the upper end portion of the second coupling portion 82 is lower than the position of the upper end portions of the first and third coupling portions 81, 83. Specifically, the upper end portion of the second coupling portion 82 is positioned in a height position that is about the same as that of a third fastening portion 35c described below. As a result, the connection rigidity between the first intake pipe group 11a and the second intake pipe group 11b is low. The second coupling portion 82 has a plurality of lateral ribs 82a that extend in the front-rear direction.

As illustrated FIG. 1 and FIG. 9, the third coupling portion 83 has an upper end portion that extends to a place in the vicinity of the upper ends of the independent intake pipe portions 11. The third coupling portion 83 has a plurality of lateral ribs 83a that extend in the front-rear direction. In the third coupling portion 83, a hose mounting portion 83b for mounting a purge hose for introducing purge gas to the surge tank portion from a canister is provided. The hose mounting portion 83b is provided so as to couple the third main passage portion 12c and the fourth main passage portion 12d to each other in the front-rear direction. Therefore, the hose mounting portion 83b has a function similar to that of the lateral ribs.

Regarding the intermediate portions 44, the intermediate portions 44 adjacent to each other are coupled to each other

via a coupling portion 44a. As illustrated in FIG. 6 and FIG. 7 to FIG. 9, in the coupling portion 44a of the intermediate portion 44, a portion continuous to the second coupling portion 82 is lower than portions continuous to the first and third coupling portions 81, 83. The intermediate portions 44 each have vertical ribs 44b that extend in the left-right direction except for the intermediate portion 44 on the frontmost side. Therefore, the rigidity of the intermediate portion 44 on the frontmost side is lower than that of the other intermediate portions 44.

Regarding the downstream-side end portions 34, the downstream-side end portions 34 adjacent to each other are coupled to each other via a coupling portion 34c. Regarding the downstream-side end portions 34, the two downstream-side end portions 34 on the rear side are shorter than the two downstream-side end portions 34 on the front sides. In the two downstream-side end portions 34 on the front side, lateral ribs 34a that extend in the front-rear direction and vertical ribs 34b that extend in the left-right direction are formed so as to be orthogonal to each other and form a knitted stitch form. In the two downstream-side end portions 34 on the rear side, the lateral ribs 34a are not formed and only the vertical ribs 34b are formed.

As illustrated in FIG. 5 and FIG. 6, end portions (in other words, portions on the most downstream side of the downstream-side end portions 34) of the independent intake pipe portions 11 on the side opposite from the surge tank portion 13 are integrated with each other and serve as the mounting portion 33 for mounting the intake manifold 10 on a cylinder block of the engine 1. The mounting portion 33 is positioned in a position apart from the surge tank portion 13 to the upper side.

The mounting portion 33 spreads in the front-rear direction so as to integrate the plurality of independent intake pipe portions 11 with each other. The mounting portion 33 is formed in flange shape. The mounting portion 33 has a plurality of fastening portions 35 (five herein) fastened and fixed to a left side face of the cylinder head of the engine 1 by bolts 62 (see FIG. 1). As illustrated in FIG. 5 and FIG. 6, the fastening portions 35 are provided on a front-side portion of the independent intake pipe portion 11 on the frontmost side, portions each between the independent intake pipe portions 11 that are adjacent to each other, and a rear-side portion of the independent intake pipe portion 11 on the rearmost side. The plurality of fastening portions 35 are arranged in a staggered form in the up-down direction with respect to the front-rear direction. Specifically, when the plurality of fastening portions 35 are referred to as a first fastening portion 35a, a second fastening portion 35b, a third fastening portion 35c, a fourth fastening portion 35d, and a fifth fastening portion 35e from the front side, the first fastening portion 35a, the third fastening portion 35c, and the fifth fastening portion 35e are relatively positioned on the lower side, and the second fastening portion 35b and the fourth fastening portion 35d are relatively positioned on the upper side. As illustrated in FIG. 6 and FIG. 8, the fifth fastening portion 35e is formed to be thicker than the first fastening portion 35a in the left-right direction. A reinforcement rib 33a is provided between the fifth fastening portion 35e and an end portion of the mounting portion 33 on the rear side and the lower side thereof. As a result, the rigidity of a portion in the periphery of the fifth fastening portion 35e is higher than that of the other fastening portions 35a to 35d.

The mounting portion 33 has a front-side mounting portion 36 relatively positioned on the front side, and a rear-side mounting portion 37 relatively positioned on the rear side. The front-side mounting portion 36 is a portion that couples

the independent intake pipe portions 11 constituting the first intake pipe group 11a to each other in the front-rear direction, and the rear-side mounting portion 37 is a portion that couples the independent intake pipe portions 11 constituting the second intake pipe group 11b to each other in the front-rear direction.

With reference to FIG. 7 and FIG. 9, a thickness W2 of the rear-side mounting portion 37 in the left-right direction (in other words, the vehicle width direction) is thicker than a thickness W1 of the front-side mounting portion 36 in the left-right direction. Specifically, the thickness W2 of the rear-side mounting portion 37 is about twice as thick as the thickness of the front-side mounting portion 36. As a result, the rigidity of the rear-side mounting portion 37 is higher than that of the front-side mounting portion 36.

Lateral ribs that extend in the front-rear direction and vertical ribs that extend in the left-right direction are formed in each of the front-side mounting portion 36 and the rear-side mounting portion 37. The lateral ribs of the rear-side mounting portion 37 are thicker than the lateral ribs of the front-side mounting portion 36. The rigidity of the rear-side mounting portion 37 is also higher than that of the front-side mounting portion 36 in the configuration of the lateral ribs.

As illustrated in FIG. 5, the surge tank portion 13 is configured to be continuous to a rear-side end portion of the intake air introduction pipe 14 and spreads to the front-rear direction and the left-right direction. The surge tank portion 13 forms an elliptical shape of which up-down direction is longer than the left-right direction when seen from the front-rear direction (see FIG. 3). The surge tank portion 13 has a plurality of reinforcement ribs 13a for enhancing the rigidity in a portion on the right side thereof.

The intake air introduction pipe 14 extends to be inclined to the right side toward the rear side. The intake air introduction pipe 14 is prevented from bulging out to the right side than the surge tank portion 13. Specifically, in a state of being mounted on the engine 1, a top portion in the intake air introduction pipe 14 on the rightmost side thereof is formed to be in a substantially same position as a right side-face portion of the surge tank portion 13 in the left-right direction.

As illustrated in FIG. 5, front-side and rear-side cross-linking portions 71, 72 that couple a surge tank base portion 31 described below and the mounting portion 33 to each other are provided in a portion of the intake manifold 10 on the right side thereof so as to extend in the up-down direction in order to ensure the rigidity of the intake manifold 10. The front-side cross-linking portion 71 is provided in a position of the first coupling portion 81 in the front-rear direction. An upper end portion of the front-side cross-linking portion 71 is coupled to a lower end portion of the front-side mounting portion 36, lower end portions of the downstream-side end portions 34 on the front side, and a lower end portion of the intermediate portion 44 on the front side. A lower end portion of the front-side cross-linking portion 71 is coupled to a portion of the intake air introduction pipe 14 on the upper side and the right side thereof. The intake air introduction pipe 14 is coupled to the surge tank portion 13. Therefore, the front-side cross-linking portion 71 is coupled to the surge tank portion 13 via the intake air introduction pipe 14. An upper end portion of the front-side cross-linking portion 71 is formed so as to couple the independent intake pipe portions 11 of the first intake pipe group 11a to each other in the front-rear direction. The rear-side cross-linking portion 72 is provided in a position of the third coupling portion 83 in the front-rear direction. An

upper end portion of the rear-side cross-linking portion 72 is coupled to a lower end portion of the rear-side mounting portion 37, lower end portions of the downstream-side end portions 34 on the rear side, and a lower end portion of the intermediate portion 44 on the rear side. A lower end portion of the rear-side cross-linking portion 72 is coupled to an end portion of the surge tank portion 13 on the upper side and the rear side thereof. An upper end portion of the rear-side cross-linking portion 72 is formed so as to couple the independent intake pipe portions 11 of the second intake pipe group 11b to each other in the front-rear direction.

A protrusion 38 that protrudes downward is formed on a lower portion of the surge tank portion 13. As illustrated in FIG. 10, the protrusion 38 is formed so as to protrude toward the right side (in other words, the engine side) in addition to the lower side. A lower end portion of the protrusion 38 is fastened and fixed to a left side face of the cylinder block of the engine 1 via a bolt 61.

In the present embodiment, the intake manifold 10 is composed of three split pieces split in the left-right direction (vehicle width direction). Specifically, the intake manifold 10 has a first split piece 30 positioned on the side closest to the engine 1 (right side), a third split piece 50 positioned on the side farthest from the engine 1 (left side), and a second split piece 40 positioned between the first split piece 30 and the third split piece 50. Each of the first to third split pieces 30, 40, 50 is separately molded in an integral manner by resin by a mold. After the molding, the first to third split pieces 30, 40, 50 are integrated with each other by being coupled with each other by vibration welding. As a result, no gaps are formed between the first to third split pieces 30, 40, 50.

The first split piece 30 constitutes a right-side portion (hereinafter referred to as the surge tank base portion 31) of the surge tank portion 13, the entirety of a front-side portion and a right-side portion of a rear-side portion (hereinafter referred to as an introduction pipe base portion 32) of the intake air introduction pipe 14, the mounting portion 33, a right-side portion 71a of the front-side cross-linking portion 71, a right-side portion 72a of the rear-side cross-linking portion 72, the downstream-side end portions 34 of the independent intake pipe portions 11, and the protrusion 38. As illustrated in FIG. 12, the second split piece 40 constitutes a left-side portion (hereinafter referred to as an other surge tank portion 41) of the surge tank portion 13, a left-side portion (hereinafter referred to as an other introduction pipe portion 42) of a rear-side portion of the intake air introduction pipe 14, right-side portions (hereinafter referred to as an independent pipe base portion 43) of the main passage portions 12 of the independent intake pipe portions 11, the intermediate portions 44 between the main passage portions 12 of the independent intake pipe portions 11 and the downstream-side end portion 34, a left-side portion 71b of the front-side cross-linking portion 71, and a left-side portion 72b of the rear-side cross-linking portion 72. The third split piece 50 constitutes left-side portions (hereinafter referred to as an other independent pipe portion 51) of the main passage portions 12 of the independent intake pipe portions 11, and the first to third coupling portions 81 to 83 of the main passage portions 12.

The intake air introduction pipe 14 is formed by fitting the first split piece 30 and the second split piece 40 with each other in the intake air introduction pipe 14. The surge tank portion 13 is formed by fitting the introduction pipe base portion 32 that is half-split in the first split piece 30 and the other introduction pipe portion 42 that is half-split in the second split piece 40 with each other.

The main passage portions 12 in the independent intake pipe portions 11 are formed by fitting the second split piece 40 and the third split piece 50 with each other in the main passage portions 12. In other words, the main passage portions 12 are formed by fitting the independent pipe base portion 43 that is half-split in the second split piece 40 and the other independent pipe portion 51 that is half-split in the third split piece 50 with each other. As illustrated in FIG. 12, in the independent pipe base portion 43, a plurality of (four herein) communication holes 43a that communicate with the inside of the surge tank portion 13 are formed so as to correspond to the independent intake pipe portions 11, respectively. Intake air is introduced to the independent intake pipe portions 11 from the surge tank portion 13 via the communication holes 43a.

The independent intake pipe portions 11 are formed across the entire longitudinal direction thereof by coupling the first to third split pieces 30, 40, 50 to each other. The portions of the independent intake pipe portions 11 that are on the downstream side of the main passage portions 12 are formed by coupling the downstream-side end portions 34 of the first split piece 30 and the intermediate portions 44 of the second split piece 40 to each other in the left-right direction.

The front-side cross-linking portion 71 is formed by fitting the first split piece 30 and the second split piece 40 with each other in the front-side cross-linking portion 71. In other words, the front-side cross-linking portion 71 is formed by fitting the right-side portion 71a of the first split piece 30 and the left-side portion 71b of the second split piece 40 with each other.

The rear-side cross-linking portion 72 is formed by fitting the first split piece 30 and the second split piece 40 with each other in the rear-side cross-linking portion 72. In other words, the rear-side cross-linking portion 72 is formed by fitting the right-side portion 72a of the first split piece 40 and the left-side portion 72b of the second split piece 40 with each other.

As in the present embodiment, when the alternator 2 is arranged in front of the intake manifold 10, the alternator 2 retreats and abuts against the intake manifold 10 at the time of the vehicle front collision. As a result, when the intake manifold 10 retreats in a pileup manner, the intake manifold 10 might interfere with the fuel pipe 3.

Meanwhile, in the present embodiment, the rigidity of the first coupling portion 81 is lower than that of the third coupling portion 83. As a result, when the alternator 2 and the intake manifold 10 abut against each other, a case where the intake manifold 10 retreats in a pileup manner can be prevented by deforming the first intake pipe group 11a by the collision load and preventing the second intake pipe group 11b from deforming as much as possible. In particular, the first intake pipe group 11a deforms and absorbs the collision load. As a result, the load received by the second intake pipe group 11b can be reduced. Therefore, the deformation of the second intake pipe group 11b can be prevented as much as possible. As a result, a case where the intake manifold 10 and the fuel pipe 3 interfere with each other at the time of a vehicle front collision can be prevented.

In the present embodiment, the first coupling portion 81 has the through hole 81b that passes through the first coupling portion 81 in the vehicle width direction. As a result, the rigidity of the first coupling portion 81 can be reduced, and the deformation of the first intake pipe group 11a at the time of a vehicle front collision can be facilitated. As a result, a case where the intake manifold 10 and the fuel pipe 3 interfere with each other at the time of a vehicle front collision can be prevented in a more effective manner.

11

In the present embodiment, the number of the lateral ribs **81a** provided in the first coupling portion **81** is smaller than the number of lateral ribs **82a** of the second coupling portion **82** and the number of lateral ribs **83a** of the third coupling portion **83**. As a result, the rigidity of the first coupling portion **81** can be reduced, and the deformation of the first intake pipe group **11a** at the time of a vehicle front collision can be facilitated.

In the present embodiment, only the intermediate portion **44** positioned on the frontmost side out of the intermediate portions **44** of the independent intake pipe portions **11** does not have the vertical ribs **44b** formed therein. As a result, the rigidity of the first intake pipe group **11a** can be reduced, and the deformation of the first intake pipe group **11a** at the time of a vehicle front collision can be facilitated.

In the present embodiment, the second coupling portion **82** positioned between the first coupling portion **81** and the third coupling portion **83** out of the first to third coupling portions **81** to **83** has the upper end portion a position of which is lower than the upper end portions of the first and third coupling portions **81**, **83**. The connection rigidity between the first intake pipe group **11a** and the second intake pipe group **11b** (in particular, the connection rigidity between the second main passage portion **12b** and the third main passage portion **12c**) can be reduced. Therefore, a case where the collision load input to the first intake pipe group **11a** is transmitted to the second intake pipe group **11b** can be prevented. As a result, at the time of a vehicle front collision, the deformation of the second intake pipe group **11b** can be prevented while deforming the first intake pipe group **11a**. As a result, a case where the intake manifold **10** and the fuel pipe **3** interfere with each other at the time of a vehicle front collision can be prevented.

In the present embodiment, the front-side cross-linking portion **71** that is provided in a position in which the first coupling portion **81** is formed in the front-rear direction and couples the mounting portion **33** and the surge tank portion **13** to each other, and the rear-side cross-linking portion **72** that is provided in a position in which the third coupling portion **83** is formed in the front-rear direction and couples the mounting portion **33** and the surge tank portion **13** to each other are included. The deformation of the first intake pipe group **11a** can be prompted by causing the collision load to be easily transmitted between the independent intake pipe portions **11** constituting the first intake pipe group **11a**. Meanwhile, in the second intake pipe group **11b**, the load after the absorption by the first intake pipe group **11a** can be appropriately received by causing the load to be easily transmitted between the independent intake pipe portions **11** constituting the second intake pipe group **11b**. The collision load is hardly transmitted between the first intake pipe group **11a** and the second intake pipe group **11b** because the connection rigidity is weak. As a result, a case where the intake manifold **10** and the fuel pipe **3** interfere with each other at the time of a vehicle front collision can be prevented.

Other Embodiments

The technology disclosed herein is not limited to the abovementioned embodiment, and substitution is possible without departing from the gist of the claims.

For example, the intake manifold structure is applied to a four-cylinder engine in the abovementioned embodiment. The present disclosure is not limited to the above, and the

12

abovementioned intake manifold structure can be applied to an engine as long as the engine is an engine having three or more cylinders.

In the abovementioned embodiment, one through hole **81b** is provided in the first coupling portion **81**, and the rigidity of the first coupling portion **81** is set to be lower than the rigidity of the third coupling portion **83**. The present disclosure is not limited to the above, and the through holes **81b** may be provided by a plurality of numbers. The rigidity of the first coupling portion **81** may be set to be lower than the rigidity of the third coupling portion **83** without providing the through hole **81b** by not providing the lateral ribs in the first coupling portion **81**, for example.

In the abovementioned embodiment, the first to third coupling portions **81** to **83** are provided between the independent intake pipe portions **11** adjacent to each other. The present disclosure is not limited to the above. The rigidity of the first intake pipe group **11a** may be set to be lower than the rigidity of the second intake pipe group **11b** by forming the third coupling portion **83** in the second intake pipe group **11b** and not forming the first coupling portion **81** in the first intake pipe group **11a**. The following is also obtained in this configuration. The first intake pipe group **11a** deforms and absorbs the collision load. As a result, the load received by the second intake pipe group **11b** can be reduced. Therefore, the deformation of the second intake pipe group **11b** can be prevented as much as possible.

In the abovementioned embodiment, the alternator is exemplified as the vehicle component. The present disclosure is not limited to the above, and the vehicle component may be a motor or a battery, for example.

The abovementioned embodiments are merely exemplifications and should not be interpreted by limiting to the scope of the present disclosure. The scope of the present disclosure is defined by the claims, and all modifications and changes belonging to a scope equivalent to the claims are within the scope of the present disclosure.

The technology disclosed herein is useful as an intake manifold structure including an intake manifold connected to a portion of a multiple cylinder engine on one side thereof in the vehicle width direction where the multiple cylinder engine is longitudinally placed in an engine room such that the cylinder array direction is in the vehicle front-rear direction.

What is claimed is:

1. An intake manifold structure comprising an intake manifold connected to a portion of an engine on one side of the engine in a vehicle width direction, the engine being longitudinally placed in an engine room such that a cylinder array direction is in a vehicle front-rear direction, the engine having three or more cylinders, wherein:

a vehicle component is arranged on a vehicle front side of the intake manifold;
a fuel pipe through which fuel flows is arranged on a vehicle rear side of the intake manifold so as to extend in an up-down direction;
the intake manifold includes

a plurality of independent intake pipe portions formed so as to branch and arranged side by side in the vehicle front-rear direction to provide one of the intake pipe portions for each of the cylinders, and a plurality of coupling portions that each couple adjacent independent intake pipe portions out of the plurality of independent intake pipe portions to each other in an integral manner; and a front-side coupling portion of the plurality of coupling portions that is the coupling portion positioned on a

13

frontmost side is configured to have a lower rigidity than a rear-side coupling portion of the plurality of coupling portions that is the coupling portion positioned on a rearmost side.

2. The intake manifold structure according to claim 1, wherein the front-side coupling portion has a through hole that passes through the front-side coupling portion in the vehicle width direction.

3. The intake manifold structure according to claim 2, wherein:

the engine is a four-cylinder engine; and
an intermediate coupling portion positioned between the front-side coupling portion and the rear-side coupling portion out of the plurality of coupling portions has an upper end portion a position of which is lower than upper end portions of the front-side and rear-side coupling portions.

4. The intake manifold structure according to claim 2, wherein the intake manifold is made of resin.

5. The intake manifold structure according to claim 3, wherein the intake manifold further includes:

a surge tank portion that is connected to one end portion of each of the plurality of independent intake pipe portions and is for distributing intake air to each of the independent intake pipe portions;
a mounting portion for integrating other end portions of the plurality of independent intake pipe portions with each other and mounting the intake manifold to the engine;
a front-side cross-linking portion disposed where the front-side coupling portion is positioned in the vehicle front-rear direction and coupling the mounting portion and the surge tank portion to each other; and
a rear-side cross-linking portion disposed where the rear-side coupling portion is positioned in the vehicle front-rear direction and coupling the mounting portion and the surge tank portion to each other.

6. The intake manifold structure according to claim 3, wherein the intake manifold is made of resin.

7. The intake manifold structure according to claim 5, wherein the intake manifold is made of resin.

8. The intake manifold structure according to claim 1, wherein:

the engine is a four-cylinder engine; and
an intermediate coupling portion positioned between the front-side coupling portion and the rear-side coupling portion out of the plurality of coupling portions has an upper end portion a position of which is lower than upper end portions of the front-side and rear-side coupling portions.

14

9. The intake manifold structure according to claim 8, wherein the intake manifold further includes:

a surge tank portion that is connected to one end portion of each of the plurality of independent intake pipe portions and is for distributing intake air to each of the independent intake pipe portions;

a mounting portion for integrating other end portions of the plurality of independent intake pipe portions with each other and mounting the intake manifold to the engine;

a front-side cross-linking portion disposed where the front-side coupling portion is positioned in the vehicle front-rear direction and coupling the mounting portion and the surge tank portion to each other; and

a rear-side cross-linking portion disposed where the rear-side coupling portion is positioned in the vehicle front-rear direction and coupling the mounting portion and the surge tank portion to each other.

10. The intake manifold structure according to claim 9, wherein the intake manifold is made of resin.

11. The intake manifold structure according to claim 8, wherein the intake manifold is made of resin.

12. The intake manifold structure according to claim 1, wherein the intake manifold is made of resin.

13. An intake manifold structure comprising an intake manifold connected to a portion of an engine on one side of the engine in a vehicle width direction, the engine being longitudinally placed in an engine room such that a cylinder array direction is in a vehicle front-rear direction, the engine having three or more cylinders, wherein:

a vehicle component is arranged on a vehicle front side of the intake manifold;

a fuel pipe through which fuel flows is arranged on a vehicle rear side of the intake manifold so as to extend in an up-down direction;

the intake manifold includes a plurality of independent intake pipe portions formed so as to branch and arranged side by side in the vehicle front-rear direction to provide one of the intake pipe portions for each of the cylinders; and

a rear-side intake pipe group, of a plurality of intake pipe groups each composed of adjacent independent intake pipe portions out of the plurality of independent intake pipe portions, is positioned closest to the vehicle rear side and has a coupling portion that integrally couples the adjacent independent intake pipe portions to each other, and a front-side intake pipe group of the plurality of intake pipe groups is positioned closest to the vehicle front side and does not have the coupling portion.
